UNITED STATES PATENT OFFICE.

ANTON ORT, OF PARIS, FRANCE, ASSIGNOR OF ONE-HALF TO HERMANN DROSSNER, OF PARIS, FRANCE.

SCALLOP-TRIMMING DEVICE FOR SEWING-MACHINES.

1,074,452.

Specification of Letters Patent. Patented Sept. 30, 1913.

Application filed January 15, 1910. Serial No. 538,328.

To all whom it may concern:

Be it known that I, ANTON ORT, manufacturer, a subject of the Emperor of Austria-Hungary, residing at 16 Rue Herold, 5 Paris, France, have invented certain new and useful Improvements in Scallop-Trimming Devices for Sewing-Machines, of which the following is a specification.

The present invention relates to an automatic device which may be attached to any scalloping or festoon-sewing machine, with one or two needles, and is intended to trim the scallop automatically as soon as it is completed; an operation which hitherto has 15 been effected only by hand.

This device comprises essentially a knife or cutter which executes a vertical reciprocatory movement for effecting the trimming and is revoluble around its vertical 20 axis so as to present itself always tangentially to the outer edge of the scallop or festoon. The material is held by two rollers located on one and the other side of the knife.

25 The accompanying drawing illustrates by way of example the application of the device forming the present invention, to a scalloping machine.

Figure 1 is a part elevation in part section of the arm of the machine. Fig. 2 is 30 a section on line 2-2 of Fig. 1. Fig. 3 is a plan view of the work table. Fig. 4 is a part elevation in part section of the cutter and its operating mechanism. Fig. 5 is a section on line 5-5 of Fig. 4. Fig. 6 is 35 a view at right angles of the sliding part of the blade-carrying arm of Fig. 4. Fig. 7 is a view from below of the spring plate seen in Fig. 4. Figs. 8 and 9 are details 40 of the rollers. Fig. 10 is an elevation at right angles to Fig. 1, as seen from the left. Fig. 11 is a detail in section of the controlling device for the eccentrics. Fig. 12 is a plan of the releasing arm for this device.

45 The cutter *a* (Fig. 4) is mounted upon a stem or carrier *a'* to which it is secured by a screw *a''*. The stem *a'* is connected by a ball joint *a''* to a double cranked lever *a''* pivoted at *b*. This lever *a''* carries a roller 50 *a''* upon which there may act an eccentric *a''*

loose upon the main shaft *c* which is journaled in the arm *d*. Under the action of the eccentric *a''* which revolves when it is coupled to the shaft *c*, the cutter *a* will therefore make a vertical up and down movement 55 for the purpose of cutting or trimming the material level with the scallop or festoon.

Around the stem *a'* is provided a socket *e* upon the lower extremity of which is screwed a presser *e'* which serves to hold 60 the material in a suitable manner during the operation of the cutter. The socket *e* receives a vertical up and down movement at its ball jointed extremity *e''* from a doubly cranked lever *e''* similar to the lever *a''*. 65 The lever *e''* carries a roller *e''* upon which there acts an eccentric *e''* loose upon the mainshaft *c* and integral with the eccentric *a''*. The lever *e''* is also pivoted at *b*. The eccentrics *a''* and *e''* are also held in 70 place upon the shaft *c* by means of a ring *c'*. They can be coupled automatically to the shaft and likewise be uncoupled therefrom. For this purpose, there is mounted upon the shaft *c* a disk *r* provided with a 75 throat *r'* and secured upon the shaft *c* by a feather *r''* so as to turn with it but to be displaceable longitudinally. In the throat of this disk there engage the two rollers *s''* of a fork *s* (Figs. 1 and 11) pivoted at *s''* 80 upon the frame *A* and having a stem *s'*. In the disk *r* there is mounted a sliding catch *t* which under the action of a spring *t'* tends to enter a hole *t''* formed in the eccentric *e''*. If the lower end of the stem *s'* receives an 85 oscillatory movement toward the left (Fig. 1), the disk *r* will move to the right and the eccentrics *a''* and *e''* will be released and the knife *a* and the presser-foot *e'* will no longer receive any movement. The stem *s'* 90 and disk *r* are brought back automatically by a spring *r''* so that as soon as the stem is no longer displaced positively toward the left, the disk *r* returns to contact with the eccentric *e''* and the spring catch *t* enters 95 the eccentric so coupling the two eccentrics to the shaft *c* of the machine.

In order that it may remain tangential to the edge of the scallop which has been formed upon the material by the needle or 100

to perform an oscillatory movement around needles α (Figs. 3 and 4), the knife a has its vertical axis and the presser-foot e' has also to swing around the same axis, in such a way as always to keep the same position in relation to the cutter. This motion is communicated to them by a sleeve f which surrounds the socket e and is revoluble in a fixed support g . Toward its lower end the sleeve f carries a pinion f' which meshes with a rack f^2 (Figs. 4 and 10) and receives from this rack an oscillatory motion. At its upper end the sleeve f carries a releasing arm f^3 provided with a pin f^4 , the position of which can be regulated along a slot f^5 ; the pin f^4 is adapted to act upon the stem s above mentioned, for the purpose of disconnecting the knife and the presser-foot as described hereinafter. The pinion, f' is secured by the screw, f^6 to the sleeve f , which is connected, as regards rotation only, to the stem, a' , by the key, h ; the latter is fixed to the stem, a' , by being sunk therein and secured to two screws, and it is slidably engaged with the sleeves, f and e , by its projecting part which fits in the longitudinal slots visible at top and bottom of the key in Fig. 14.

In order to effect the cutting or trimming, the knife a coacts with a round plate i traversed by a rectangular hole i' through which there passes the knife a . The latter is provided with an extension a^6 serving as a guide and it is, moreover, pressed constantly back by a small spring plate i^2 against the edge (Figs. 3 and 7) of the hole i' , so as to effect a clean cut in conjunction with this cutting edge, even if the material is hard to cut or if the knife itself is blunted. From the foregoing it will be understood that the plate, i is provided with a rectangular opening in one end of which the extremity of the knife a fits, said extremity being held in place by the movable plate, i^2 which is pressed against it by a spring, as shown in Fig. 7.

The round plate i (Fig. 3) is arranged in an opening j' in a plate j adapted to slide transversely in the work table k of the machine, so as to allow the cutter a , which has only a vertical reciprocating motion and an oscillating motion about its axis, to cut either at the swell S of the scallop (Fig. 3) or at the cusp or point P ; the work is fed or guided both transversely and longitudinally as will be described hereafter. The plate i revolves, like the cutter, about its vertical axis and is for this reason made integral with a pinion i^3 (Fig. 4) adapted to perform an oscillatory motion under the action of a rack i^4 (Figs. 4 and 10).

The rack f^2 is attached by screws (Fig. 10) to the rack i^4 which is connected by means of a part m^x and a wing nut l work-

ing in a slot m^2 to a lever arm m which is pivoted at m' . This arm receives an oscillating movement in a known manner from a drum n provided with a cam-groove n' in which there travels a pin n^2 screwed to the arm m . The oscillatory movement communicated by the drum n to the lever m reciprocates the racks f^2 and i^4 and so oscillates the pinions f' and i^3 . Consequently the knife a and the opposing plate i rotate in such a way that the cutter remains tangential to the edge of the scallop so as to effect the trimming in a suitable manner.

In order to guide and feed the scalloped material longitudinally over the plates i and j , after the scallop has been produced by the needles α (Figs. 4 and 3), two small rollers p p' are arranged above the plate j . These revolving rollers are preferably coated with rubber to obtain good adhesion while they press the scalloped material against the plate j and so feed it in the longitudinal direction. The plate j has a pin j' engaged between collars j^2 on the spindle q and performs a transverse movement corresponding to the transverse feed imparted to the material for the shaping of the scallop in such a way that each point of the outer edge of the scallop comes in turn under the knife a . The roller p receives its rotary movement from the shaft q (Fig. 3) of the drum n and it operates the roller p' by toothed pinions p^2 p^3 (Figs. 8 and 9). In this way the material receives a positive feed after leaving the needles α .

The plate, j , and rollers, p , p' , receive their reciprocating motion from the shaft, q , which has itself a longitudinal reciprocating motion. The rollers are operated directly, the roller, p , being mounted upon the shaft, q . The plate, j , is operated by means of its pin, j' , (Fig. 10,) engaged between the collars, j^2 , on the spindle or shaft, q , said spindle or shaft itself receiving reciprocating motion from the cam-drum, n , by means of the attachment, q' , which is connected by a rod as m^{xx} to the pendulum lever, m^3 , as will be seen in Fig. 1. These parts are similar to the parts, m and m^x , which actuate the sliding racks, f^2 and i^4 . In addition to its reciprocation, the shaft or spindle, q , has also a radial motion, received direct from the ratchet wheel, 10, which is seen in Fig. 10, between the end of the frame and the drum, n .

The spindle or shaft, q , on which the drum, n , is mounted is really a telescopic shaft, the inner portion carrying at one end the feed roller, p , and having at the other end a flattened portion, 12, Fig. 1, which is engaged by a projection, 13, secured on the face of the drum, n . The outer portion or sleeve through which the inner part of the shaft slides longitudinally, is connected to

the drive wheel or ratchet, 10, and the drum, *n*, is fixed upon this sleeve by any well known means. The inner slideable part of the shaft has a groove or double collar, 14, to engage a fork upon the attachment, *q'*. The rollers *p* *p'* are mounted in frames, *p*¹⁰, *p'*¹⁰, connected by screws, *p*⁶, engaged in slots, *p*⁵, and are adjustable according to the work being done and they may be replaced 10 for example by larger ones in the case of larger scallops.

When the knife reaches the end *P* of a scallop-tooth, in order to continue the trimming and commence the following tooth, it 15 must turn in the opposite direction from the first so as to return to the position which it has to occupy to commence the trimming of a tooth. This change of direction in its oscillation results from the fact that the rack *f*² has at this moment reached the end of its stroke and returns in the opposite direction under the action of the drum *n*. The return of this rack oscillates the pinion *f'* in the opposite direction so that the knife then 20 turns oppositely around its vertical axis. Since the same applies of course to the presser-foot *e'*, these two parts will therefore occupy always the desired position for beginning to trim each tooth. In order, 25 however, to prevent the knife from going too far when the point *P* of the tooth approaches, which would cause cutting of the festoon, and in order to allow it to return to its original position, it is disconnected 30 shortly before reaching this point, for example three scallop stitches or points before. This result is obtained by making the pin *f'* of the arm *f*² engage precisely at this moment with the stem *s'* which operates the 35 clutch-disk *r*, so that the eccentrics are disconnected and the knife and presser-foot held stationary. As soon as the rack *f*² returns in the opposite direction the pin *f'* releases the stem *s'* and the eccentrics are engaged automatically by the spring catch *t*, 40 so that the knife resumes its motion.

In order that the knife *a* may be placed out of action when desired for a length of time, the levers *a*⁵ and *e*⁵ are mounted eccentrically upon their pivot *b* (Figs. 1 and 2) so that the turning of this pivot by means of a knob *b'* or the like will lower these levers and their rollers *a*⁶ and *e*⁶ which are in this way removed from the action of the eccentrics *a*⁵ and *e*⁵. The distance from the needle or needles *x* to the knife *a* must obviously be equal to the width of the scallop being formed by the machine. The plate *i* and the knife *a* are therefore adjustable in 55 relation to the needles. The support *g* is mounted on a bracket *g'* slideable upon the frame *A* and having slots *g*² engaged by screws *g*⁴ by which it may be clamped at any desired position.

The rotary movement of the knife *a*, the 65 socket *e* and the plate *i* may be regulated by moving the nut *l* along the slotted part *m*. The depth of the scallop is regulated in the known manner by means of a wing nut *l'* (Fig. 1).

The operation of the device will be understood at once from the preceding description. The material is fed so as to present in turn to the knife all parts of the outer edge of the scallop. In proportion as 70 it passes over the plate *i* and under the cutter *a*, the latter trims it along the scallop remaining constantly tangential to the exterior outline of the latter. All the parts are adjustable or exchangeable so that festoons 75 or scallops of all dimensions may be produced.

The improved device is simple and practical and allows of effecting automatically and in a careful manner the operation of 80 trimming which has hitherto been performed only by hand and at great pains on the part of the operator.

Having thus described my invention, what I claim as such and desire to secure by Letters Patent is:—

1. A scallop trimming device for sewing machines, comprising a trimming knife, a main shaft, an eccentric upon the mainshaft, means for reciprocating said knife by the rotation of said eccentric, means for connecting said eccentric to said mainshaft, means for guiding the material having a longitudinal and transverse feed, and means for keeping said knife tangential to the outer 95 edge of the scallop.

2. A scallop trimming device for sewing machines, comprising a trimming knife, means for reciprocating said knife, means for guiding the material, a pinion, means 105 for transmitting the rotation of said pinion to said knife, a rack engaging said pinion and a cam-drum, and means for reciprocating said rack, said means being controlled by the scallop-controlling cam drum.

3. A scallop trimming device for sewing machines, comprising a trimming knife, means for reciprocating said knife, means for guiding the material, said guiding means including rollers, said rollers being on opposite sides of the knife, positive means for rotating said rollers, and means for keeping said knife tangential to the outer edge of the scallop.

4. A scallop trimming device for sewing 120 machines, comprising a trimming knife, a main shaft, an eccentric upon the mainshaft of the machine, means for reciprocating said knife by the rotation of said eccentric, means for guiding the material, a presser-foot co-acting with said knife, a second eccentric upon the mainshaft of the machine, means for reciprocating said presser-foot by 125

- the rotation of said second eccentric, means for connecting said eccentrics to said main-shaft, and means for keeping said knife tangential to the outer edge of the scallop.
5. A scallop trimming device for sewing machines, comprising a trimming knife, means for reciprocating said knife, means for guiding the material, means for revolving said knife upon its axis in accordance with the direction of the outer edge of the scallop, and means for disconnecting said knife-reciprocating means just before the end of each scallop and for reconnecting at the beginning of the next scallop, said knife being meanwhile returned to its original position.
6. A scallop trimming device for sewing machines, comprising a trimming knife, means for reciprocating said knife, means for guiding the material, a socket inclosing said knife, an arm mounted on said socket, means for revolving said knife, socket and arm upon their axis in accordance with the direction of the outer edge of the scallop, said arm disconnecting said knife-reciprocating means in an extreme angular position, and means for automatic reconnection thereafter.
7. A scallop trimming device for sewing machines, comprising a trimming knife, a main shaft, an eccentric upon the main-shaft of the machine, means for reciprocating said knife by the rotation of said eccentric, means for guiding the material, a socket inclosing said knife, a presser-foot secured upon the lower end of said socket, said presser-foot co-acting with said knife, a second eccentric upon the main-shaft of the machine, means for reciprocating said socket and presser-foot by the rotation of said second eccentric, said eccentrics being in suitable angular relation, a revolute sleeve surrounding said socket, an arm mounted upon said sleeve, means for revolving said knife, sleeve and arm upon their axis in accordance with the direction of the outer edge of the scallop and disconnectible means for connecting said eccentrics to said main-shaft, said last means being disconnected by said arm in an extreme position and automatically reconnected thereafter.
8. A scallop trimming device for sewing machines, comprising a trimming knife, a main shaft, an eccentric upon the main shaft of the machine, a lever, a pivot for said lever, said lever being connected to said knife, a roller carried by said lever, said roller adapted to travel upon said eccentric and thereby to cause the oscillation of said lever and the reciprocation of said knife, and an eccentric device for removing said roller from contact with said eccentric by varying the position of said pivot.
9. A scallop trimming device for sewing machines, comprising a trimming knife, means for reciprocating said knife, means for guiding the material, said guiding means including rollers, a plate coacting with said knife, and means for revolving said knife and plate upon their common axis in accordance with the direction of the outer edge of the scallop, said knife, plate and rollers being adjustable in position and in movement to suit scallops of varying dimensions.
10. A scallop trimming device for sewing machines, comprising a trimming knife, means for reciprocating said knife, means for guiding the material having a longitudinal and a transverse feed, said guiding means including rollers, said rollers being on opposite sides of the knife, positive means for rotating said rollers, a plate mounted in the work table of the machine, said rollers being mounted on said plate, said plate adapted to slide transversely in accordance with the scalloping, and means for keeping said knife tangential to the outer edge of the scallop.
11. A scallop trimming device for sewing machines, comprising a trimming knife, said knife being at a distance from the stitching point equal to the width of one scallop, means for guiding the material having a longitudinal and a transverse feed, said guiding means including rollers, said rollers being on opposite sides of the knife, positive means for rotating said rollers, a plate mounted in the work table of the machine, said rollers being mounted on said plate, said plate being adapted to slide transversely in accordance with the scalloping, a socket inclosing said knife, a presser-foot secured upon the lower end of said socket, said presser-foot coacting with said knife, a main shaft, two eccentrics loose upon the main-shaft, said eccentrics being integral and in suitable angular relation, a clutch-disk slidably keyed upon the main-shaft, a spring-catch mounted upon said clutch-disk and adapted to engage said eccentrics, a striking fork controlling said clutch disk, a pair of levers, a common pivot for said levers, said pivot having an eccentric adjustment, rollers carried by said levers, said rollers traveling upon said eccentrics respectively, one of said levers engaging the upper extremity of said knife, the other of said levers engaging the upper extremity of said socket, a sleeve inclosing said socket, an arm mounted upon said sleeve, a pinion secured upon said sleeve, a rack engaging said pinion, a revolute circular plate fitting in a transverse slot in said sliding plate, said knife being guided through said circular plate, a blade carried by said circular plate, said blade coacting with said knife, a spring plate press-

ing said knife against said blade, a pinion connected to said circular plate, a rack engaging said pinion, a scallop forming cam drum, said racks being connected together and being operated by the scallop-forming cam-drum, said arm engaging said striking fork to disconnect said eccentrics in an extreme position and said eccentrics being au-

tomatically reconnected by said spring-catch thereafter.

In testimony whereof I affix my signature in presence of two witnesses.

ANTON ORT.
